CLAIM

The ornamental design of a cartridge with a bottom right-handed thread for injecting a fluorescent dye or lubricant into an air-conditioning or refrigeration system, as shown and described.

DESCRIPTION

FIG. 1 is a front view of the cartridge with a bottom right-handed thread for injecting a fluorescent dye or lubricant into an air-conditioning or refrigeration system.

FIG. 2 is a back view of the cartridge with a bottom right-handed thread for injecting a fluorescent dye or lubricant into an air-conditioning or refrigeration system.

FIG. 3 is a left side view of the cartridge with a bottom right-handed thread for injecting a fluorescent dye or lubricant into an air-conditioning or refrigeration system.

FIG. 4 is a right side view of the cartridge with a bottom right-handed thread for injecting a fluorescent dye or lubricant into an air-conditioning or refrigeration system.

FIG. 5 is a top view of the cartridge with a bottom right-handed thread for injecting a fluorescent dye or lubricant into an air-conditioning or refrigeration system; and,

FIG. 6 is a bottom view of the cartridge with a bottom right-handed thread for injecting a fluorescent dye or lubricant into an air-conditioning or refrigeration system.
